UNITED STATES PATENT OFFICE.

HAROLD W. NICHOLS, OF MAPLEWOOD, NEW JERSEY, ASSIGNOR TO WESTERN ELECTRIC COMPANY, INCORPORATED, OF NEW YORK, N. Y., A CORPORATION OF NEW YORK.

RELAY.

Application filed April 16, 1920. Serial No. 374,458.

To all whom it may concern:

Be it known that I, HAROLD W. NICHOLS, a citizen of the United States, residing at Maplewood, in the county of Essex and State 5 of New Jersey, have invented certain new and useful Improvements in Relays, of which the following is a full, clear, concise, and exact description.

This invention relates in general to electromagnetic devices and particularly to relays of the type used in telegraphic systems.

The object of the invention is to provide a simple and positive method and system for operating relays of the polarized and 15 alternating current types.

Such relays comprise an armature adapted to be electromagnetically energized and two electromagnetic poles which influence the armature in alternate ways depending 20 upon the character of the current impulses applied.

In accordance with this invention the windings are normally not energized. When line impulses are impressed on the 25 line, such impulses are relayed to the armature winding and to one or the other of the pole electromagnets depending upon the polarity of the current impulse. The relayed impulses are of uniform polarity so that whenever energized, the armature has 30 the same polarity.

In its application to A. C. relays, one of the pole electromagnet windings is reversed so that one pole, when energized, always 35 repels the armature while the other pole when energized, always attracts the armature. Thus the armature is influenced always to swing in the same direction regardless of the polarity of the line impulse.

By virtue of the fact that the windings 40 of the relay are normally not energized, the armature may be biased by means of a very weak spring. Speed of operation and freedom from chattering on contacts are thereby obtained.

In the invention in its preferred form, the means employed for relaying the impulses consists of a pair of blocked thermionic repeaters, which are preferred for the purpose because of their positive and immediate

response. Other relaying devices, however, may be employed for this purpose and the same is contemplated in this invention.

The invention may be understood more completely by reference to the drawings in which Fig. 1 shows the manner of applying the invention to a simple polarized relay; Fig. 2 illustrates a similar arrangement where a source of alternating current is used for actuating the relay; and Fig. 3 55 and Fig. 4 show somewhat similar applications of the invention to alternating current relays. In the various figures, similar reference characters refer to similar parts.

In Fig. 1, a pair of electromagnet windings 1, 2 are supported by a core of magnetic material having poles 3 and 4. The core supports an armature 6 which is adapted to swing between the poles 3 and 4. The armature 6 is adapted to be electromagnetically energized by the winding 5. A coil spring 7 biases the armature 6 to stand in a neutral position between contacts 8 and 9. 65

Two thermionic repeaters 10 and 11 are provided and are connected so that winding 1 is in the plate circuit of the repeater 10 and winding 2 is in the plate circuit of repeater 11. The winding 5 is connected in the common return of the plate circuits of repeaters 10 and 11. 70

The line 12 and 13 on which the line impulses are to be impressed is shunted by a resistance 14. The grid circuits of repeaters 10 and 11 are bridged across the resistance 14 so that the impulses impressed on the line 12, 13 are adapted to produce charges 85 in the grids of the repeaters 10 and 11. Batteries 17 are provided to heat the filaments of the repeaters 10 and 11. A source of direct current 16 is provided in the common branch of the plate circuits of the repeaters 10 and 11, but no current flows in these circuits because of the negative charges 90 on the grids set up by the source of direct current 15.

When a positive impulse is impressed on the line 13, the grid of repeater 11 is charged less negatively and the grid of repeater 10 is charged more negatively than under normal conditions. This allows a 100

flow of current in the plate circuit of repeater 11 and consequently, the windings 2 and 5 are energized whereby the armature 6 and the pole 4 attract each other and contact is made between the armature 6 and the contact 9. No current flows in the plate circuit of repeater 10 since it is blocked by the negative charge of the grid. When a negative impulse is impressed on the line 13, 10 the grid of repeater 11 becomes more negatively charged and the grid of repeater 10 becomes less negatively charged. A flow of current results in the plate circuit of repeater 10 whereby the windings 1 and 5 15 become energized and the armature 6 is attracted toward the pole 3 making contact with the contact 8. No current will flow in the plate circuit of repeater 11 on account of the negative charge on the corresponding 20 grid.

Since current can flow in only one direction through the plate circuits of the repeaters 10 and 11, the armature 6 is energized always to be of the same polarity 25 as is also the case of the poles 3 and 4.

Fig. 2 shows a similar arrangement in which alternating current is used as the current supply for energizing the windings 1, 2 and 5. A transformer 19 is provided 30 in which the secondary winding is connected, half in the plate circuit of the repeater 10 and half in the plate circuit of the repeater 11 and whose primary is connected to a source 18 of high frequency alternating current. One half the wave is thus used for energizing the winding 1, and the other half of the wave is used to energize the winding 2. The circuit arrangement being, in effect, a rectifying means, the winding 5 is energized similarly by both 35 halves of the current wave. A condenser 22 may be connected across the secondary winding of the transformer 19 to supply the momentary deficiency of current due to the 40 alternations.

Fig. 3 shows an arrangement similar to that of Fig. 1, which adapts the relay to be used as an alternating current relay. The winding 20 is reversed so that the poles 3 50 and 4 when energized are of opposite polarity. A transformer 21 may be substituted for the resistance 14 bridging the primary across the line 12, 13 and differentially connecting the secondary in the grid circuits of the repeaters 10 and 11. The winding 1, when energized under the influence of one half the wave impressed on the line 12 and 13, energizes the pole 3 positively. Winding 20, under the influence of the other 55 half of the alternating current wave impressed on the line 12 and 13, energizes the pole 4 negatively. Both halves of the alternating current impressed, energize the winding 5 to magnetize the armature 6 positively. Thus, when the pole 3 and the ar-

mature 6 are energized they repel each other so that armature 6 and contact 9 contact. When the pole 4 and the armature 6 are magnetized they attract each other also to make contact between the armature 6 and 70 contact 9. The armature 6, therefore, responds in only one direction to alternating current impressed on the line.

Fig. 4 shows an arrangement similar to Fig. 3 for operating the relay by alternating current, but uses a source of alternating current 18 instead of the source of direct current 16 for energizing the relay windings. The alternating current source 18 is applied in a manner similar to the 80 way in which it is applied in Fig. 2.

What is claimed is:

1. In a signaling system, a biased armature, means for polarizing said armature, two operating windings arranged to cooperate with said armature so as to effect its actuation, a signaling path, means for energizing one of said operating windings only upon the receipt of positive current impulses, and means for energizing the 90 other of said operating windings only upon the receipt of negative current impulses. 85

2. In a signaling system, a biased armature, two operating windings arranged to cooperate with said armature so as to effect 95 its actuation; a third winding for polarizing said armature, a signaling path, means for energizing one of said operating windings only upon the receipt of positive current impulses, and means for energizing the 100 other of said operating windings only upon the receipt of negative current impulses. 100

3. In a signaling system, a signaling path, two operating windings independently responsive to current impulse from said 105 signaling path, and a biased polarized armature, said armature being actuated solely by the coaction of the armature magnetic flux and the flux induced by said operating windings. 110

4. In a signaling system, a signaling path, a plurality of operating windings cooperating with a biased electromagnetic armature, said armature being actuated solely by the coaction of the magnetic flux of said 115 armature and the magnetic flux induced by said operating windings, and relay means controlled by current impulses from said signaling path for energizing said armature and selectively energizing said operating windings depending upon the character 120 of the current impulses. 120

5. In a signaling system, a biased armature, direct current means for polarizing said armature, two operating windings arranged to cooperate with said armature so as to effect its actuation, a signaling path, means for energizing one of said operating windings only upon the receipt of positive current impulses, and means for en- 125 130

ergizing the other of said operating windings only upon the receipt of negative current impulses.

6. In a system for operating a relay having a pair of operating windings adapted to influence an electromagnetic armature, a thermionic repeater cooperating with each of said operating windings and adapted

to relay impulses of current thereto and to the electromagnetic armature, and a source of positive and negative current impulses selectively controlling the flow of current in both said thermionic repeaters.

In witness whereof, I hereunto subscribe my name this 14th day of April A. D., 1920.

HAROLD W. NICHOLS.
